PORTABLE RADIO CABINET

Melvin H. Boldt, Glenview, Ill., assignor to Zenith Radio Corporation, Chicago, Ill., a corporation of Delaware

Filed Feb. 3, 1966, Ser. No. 911

Term of patent 14 years

(Cl. D56—4)

FIG. 1

FIG. 2

FIG. 3

FIGURE 1 is a front elevational view of a portable radio cabinet showing my new design;

FIGURE 2 is a left side elevational view thereof; and

FIGURE 3 is a top plan view as seen from line 3—3 of FIGURE 2.

The right side not shown, is the same as the left side and the back and bottom are plain and unornamented.

The dominant features of my design reside in those portions of the drawing shown by means of full lines.

I claim:

The ornamental design for a portable radio cabinet, substantially as shown and described.
